UNITED STATES PATENT OFFICE.

WILLIAM WATTIE, OF WORCESTER, MASSACHUSETTS, ASSIGNOR TO THE
KNOWLES LOOM WORKS, OF SAME PLACE.

SHUTTLE-HOLDER ATTACHMENT FOR LOOMS.

SPECIFICATION forming part of Letters Patent No. 380,736, dated April 10, 1888.

Application filed September 23, 1887. Serial No. 250,484. (No model.)

To all whom it may concern:

Be it known that I, WILLIAM WATTIE, a citizen of the United States, residing at Worcester, in the county of Worcester and State of Massachusetts, have invented certain new and useful Improvements in Shuttle-Holder Attachments for Looms; and I do hereby declare that the following is a full, clear, and exact description thereof, which, in connection with the drawings making a part of this specification, will enable others skilled in the art to which my invention belongs to make and use the same.

My invention relates to looms, and more particularly to an attachment secured upon the loom side for holding the extra shuttles used in the loom; and the object of my invention is to provide on a loom a simple and readily-accessible receptacle for the extra shuttles, which are kept in readiness to be put in the loom when the filling runs out.

Referring to the drawings, Figure 1 is a rear elevation of a portion of a loom with my invention applied thereto. Fig. 2 is a section on line X X, Fig. 1, looking in the direction of the arrow, same figure; and Fig. 3 is a perspective view of the shuttle holder attachment and a supplementary attachment for holding the bobbins detached from the loom.

In the accompanying drawings, 1 is the loom-side, 2 the crank-shaft, 3 the bottom shaft, 4 the lay, and 5, Fig. 1, the projecting drop-box lay end, of an ordinary loom. The part marked 6 is a stand bolted to the loom side, which carries on the inside a series of shelves, 7, set at such a distance apart that the shuttles 18, Fig. 2, used on the loom will pass freely between them. Formed on the edges of the shelves 7 are flanges 8 and 9, a sufficient distance apart to admit a shuttle between them and high enough to prevent a shuttle being taken side-

wise from the shelves. The end of each shelf 7 toward the back of the loom is provided with a flange, 10, in which is set, preferably, a small wood or leather disk, 11, against which 45 the tip of the shuttle rests when on the shelf. The shelves 7 are inclined toward the back, so that gravity prevents the jar of the loom from working the shuttles off the shelves.

In order to retain the shuttle on the top shelf, 50 the upper end of the stand 6 is turned inward and projects over the shuttle. Fastened also to the stand 6 in Fig. 1 is a supplementary attachment consisting of a box, 12, which projects outward any distance not exceeding that 55 of the lay end 5, and is stayed by the brace 13, resting against the loom-side. The width of the box is about the same as the length of the cops used, and the depth as desired.

In Fig. 1 the box 12 is represented with divisions 14, separating the different colors of cops.

When the filling to be used is wound on bobbins, instead of cop-tubes, I prefer to use a rack, 15, Fig. 3, provided with pins 16 extending up therefrom for the reception of the bobbins 17, in lieu of the box 12. (Shown in Figs. 1 and 2, and above described.)

Having thus described my invention, what I claim as new, and desire to secure by Letters 70 Patent, is—

The combination, with a loom-side, of the stand 6, bolted thereto, and a series of inclined stationary shelves, 7, having side flanges and an end flange supported on said stand for furnishing a supplementary attachment for the reception of extra shuttles, substantially as shown and described.

WILLIAM WATTIE.
